US00D986073S

(12) **United States Design Patent** (10) Patent No.: **US D986,073 S**
Schätzle et al. (45) Date of Patent: **** May 16, 2023**

(54) **DEVICE FOR MEASURING FILL LEVELS OR PRESSURE**

(71) Applicant: **VEGA Grieshaber KG**, Wolfach (DE)

(72) Inventors: **Ralf Schätzle**, Schiltach (DE); **Fabian Witt**, Schiltach (DE); **Jürgen R. Schmid**, Ammerbuch (DE)

(**) Term: **15 Years**

(21) Appl. No.: **35/514,236**

(22) Filed: **May 29, 2019**

(80) **Hague Agreement Data**

Int. Filing Date: **May 29, 2019**

Int. Reg. No.: **DM/210251**

Int. Reg. Date: **May 29, 2019**

Int. Reg. Pub. Date: **Sep. 18, 2020**

(51) **LOC (14) Cl.** **10-07**

(52) **U.S. Cl.**

USPC **D10/46**

Primary Examiner — George D. Kirschbaum

Assistant Examiner — Lillian Windham

(57) **CLAIM**

We claim the ornamental design for a device for measuring fill levels or pressure, as shown and described.

DESCRIPTION

1.1 : Left

1.2 : Right

1.3 : Front

1.4 : Back

1.5 : Top

1.6 : Bottom

1.7 : Perspective

1 Claim, 7 Drawing Sheets
